UNITED STATES PATENT OFFICE.

ANDRÉ BEURDELEY, OF PARIS, FRANCE.

ARTIFICIAL LEG.

1,407,369.

Specification of Letters Patent. Patented Feb. 21, 1922.

Application filed July 19, 1920. Serial No. 397,364.

(GRANTED UNDER THE PROVISIONS OF THE ACT OF MARCH 3, 1921, 41 STAT. L., 1313.)

To all whom it may concern:

Be it known that I, ANDRÉ BEURDELEY, engineer, citizen of the French Republic, residing at Paris, Department of the Seine, in France, and having P. O. address 79 Rue de Clichy, in the said city, have invented certain new and useful Improvements in Artificial Legs, (for which I have filed applications in France Dec. 11, 1918, and March 7, 1919;) and I do hereby declare the following to be a full, clear, and exact description of the invention, such as will enable others skilled in the art to which it appertains to make and use the same.

15 The present invention relates to artificial limbs and particularly to artificial legs intended to replace, as near as possible, both from outward appearance and manipulation, an amputated limb.

20 The principal object of the invention is to produce a device of the character indicated, wherein all the parts are articulated and connected in such a manner as to fulfill all the requirements necessary in an efficient apparatus of this kind, and the thigh parts are so designed as to provide the amputated subject with a flexible support under the buttock by means of the hip bone which is a natural point of support, and to fix the amputated member by means of broad garters, one of which prevents the stump from moving out of the stock of the lower leg portion.

25

30

Another important feature is that the support can be adjusted as required by the amputated subject according to the pressure the latter wishes to place respectively upon the knee or the buttock in consequence of temporary sensitiveness or for any other reason. The articulation of the knee which is integral on the one hand with the upright part of the thigh and on the other hand with the lower leg portion, is eccentric. Its eccentricity is equal to the lengthening movement made by the leg in moving from the upright to the seated position when the amputated subject bends his leg, but there is no displacement relatively to the apparatus on account of the variations in length during this movement.

Still another feature is the particular means by which the articulation uniting the foot to the lower leg portion, namely the ankle, can be displaced in two directions at right angles to one another, the first of these

is in a plane form front to back, in a manner similar to the movement employed in walking. The second, the amplitude of which is reduced, takes place in a frontal plane and this is the lateral play which permits the foot to adjust itself to the irregularities of the ground.

The part of the foot which represents the toes is also articulated and arranged in such a manner as to restore the function of this part of the foot as in the case of a normal person, the function being to continue the propulsion when the heel has left the ground.

The external part of the ankle articulation is efficiently protected by a rubber bracelet of special form, which joins the separate parts without folds in a continuous manner.

The invention is illustrated in the accompanying drawings, in which:

Fig. 1 is a view of the complete apparatus in side elevation;

Fig. 2 is a vertical sectional view of the lower portion of the apparatus, as illustrated in Fig. 1;

Fig. 3 is a view of the apparatus in rear elevation;

Figs. 4 and 5 are enlarged sectional detail views of the foot and ankle connections, illustrating the flexible joint construction;

Fig. 6 is a view illustrating the manner of applying the complete device to the wearer;

Fig. 7 is a diagrammatic view illustrating the device as adjusted to the wearer;

Fig. 8 is an enlarged sectional detail view of the hinged knee joint construction;

Fig. 9 is a modification illustrating another means of adjusting the height of the upper part of the apparatus;

Fig. 10 is another modification illustrating another form of the upper sliding connection to which the hip securing straps or bands are attached; and

Figs. 11, 12, 13 and 14 illustrate various modifications of means for adjusting the height of the upper part of the apparatus and means for securing the same to the wearer.

Referring to the drawings in detail, the apparatus comprises a lower leg portion 1, preferably hollow, the foot member 2 provided with a toe extension 3, and an upper thigh embracing framework which is adapted to be held in position and secured to the wearer by straps or bands 4, 5 and 6.

The parts of the thigh embracing frame-

work, Figs. 1, 3, 8 and 9, are formed essentially of two hollow metallic uprights of oval shape in three pieces, 7, 8 and 4¹ which can slide in one another, the part 8 carrying 5 at its lower extremity an eccentric for the purpose to be hereinafter more fully set forth.

At the top is the supporting band 4, which is shaped to follow the contour of the thigh 10 at the height of the hip bone and receives that part of the weight of the amputated subject's body which he desires to put upon it. This band terminates at each of its extremities in an eyelet hole by means of which 15 it is attached to a bolt or rivet in the part 4¹, the amputated member being also fixed by two additional bands of ample width 5 and 6, the band 5 preventing the inversion produced by applying pressure to the band 20 4, while the band 6 prevents the stump from moving out of the stock of the lower leg portion.

The part 7 referred to above can slide with a gentle friction in the part 8, and 25 the part 13 is provided with a collar which may be tightened by a bolt, thus allowing the height of the hip 4 to be adjusted with precision, and in addition, on the part 7 a spring 14 is mounted, 30 the point of support of which is located in a collar 14¹ fixed to the part 7. The part 4¹ can also slide in the part 7 and the force exerted by the band 4 is transmitted to the springs 14—14, through the part 4¹ which 35 presses on the lower end of it. A small screw placed at the bottom of the part 4¹ limits the movement of the springs and the point of this screw passing through a small groove 15 cut out in the part 7. The adjustment of the height may also be effected 40 in another manner which is shown in Figure 9. In this construction the part 7 is perforated at its lower end by a number of small holes 12 while at the upper end of 45 the part 8 there is a corresponding hole. The height can now be adjusted in a very simple manner by means of a small pin 11 having a flat head, this pin being held in position by a spring 10, an arrangement 50 which allows the height adjustment to be effected very conveniently.

In order to increase the security against injury to the perineum, which might otherwise be caused by the impact of the part 4¹ 55 against it, a modified arrangement of the part 4¹ is provided. With this object in view, the part 4¹ is designed as shown in Fig. 10. The part 4¹¹ is much shorter than the part 4¹ but this difference is compensated for by a backward extension of the former part, at the top of which there is a hole 4¹¹¹ from which the band 4 is suspended.

The thigh parts terminate in an eccentric 65 16¹, the details of which are shown in Figure

8 in two sections. The part 9 attached to the lower leg portion terminates in a fork 16 forming a mortise, the part 8 ending in a collar supporting the eccentric 16¹. The two axes of the parts 9 and 8 are slightly 70 eccentric and a square bolt passes through the axis 9, a bronze piece 16¹¹ which forms the eccentric being mounted on this bolt. The fixing garter 6 is of the customary form and is laced up on the outside as usual; it 75 is attached to the thigh uprights by a counterplate which holds it against the upright by means of small bolts, the heads of which are imbedded in the plate. This method of assembly facilitates the removal 80 of the parts and enables them to be cleaned. The foot 2 is united to the lower leg portion by a double articulation, the constructional details of which are shown in Figure 4 while the complete arrangement is shown in 85 Figure 2.

The two axes of rotation may be clearly seen in Figs. 4 and 5, the transverse axis being represented by the pin 27 and the longitudinal axis being formed by the hollow half-cylinder 28, which serves in addition as an oil box and enables the pin 27 to be lubricated through the small passages 31, the oil being introduced through a small opening 28¹ covered with a plug. The 90 longitudinal axis 28 is reinforced at its center by a rib 29, and interposed between the member 28 and the foot is a leather pad 32.

The return movements of the foot in a longitudinal direction are effected by means 100 of two flexible connections fixed on the one hand to the foot, and on the other, to a specially shaped part which is integral with the lower portion of the lower leg portion. The pin 27 lies in a small bearing 30 imbedded in the hollow axis 28. The return movement is effected backwards by a special cylindrical part 19 filled with oil and fitted with a piston actuated by a spiral spring and is connected to the foot at the back 105 by a hook bolt 19¹, while the stem of the piston is connected to the lower leg portion by a screw which enables the tension of the spring to be adjusted, and consequently the movement of the ankle in the direction from 110 back to front. The return movement for the front part of the foot, which can be adjusted, is effected by means of a rubber spring 20 connected on the one side to the lower leg portion and hooked at the other 115 end to a stem 22 provided at its extremity with a screw-thread, the tension of the spring being adjusted by means of the screw 21.

The return movements of the foot in a 125 transverse direction are effected in the following manner:

Two stirrups 24 provided with bronze bushings 26 are mounted on the pin 27, the lower part of these stirrups taking the form 130

of a stem 25 provided at its extremity with a screw-thread. Spiral springs 23 are threaded on to these stems, the springs being compressed by means of the screw 5 against the upper part of the cavity, provided to receive them in the interior of the foot. The effect of all lateral movement will be to cause the hollow half cylindrical axis 28 to oscillate, thus compressing first one 10 and then the other of the springs which will subsequently cause the foot to return to its normal position.

The articulation as described above is protected by a rubber bracelet 18, Fig. 1. 15 The articulation at the extremity of the foot 3 is illustrated in Figure 2 and consists of a spring 34 which returns the foot when it moves round the articulation 35, the upper part being protected by a leather covering 33. Figure 6 shows another method of articulating the extremity 3 of the foot. The return movement is effected here by means of an arrangement which allows the tension of a return spring to be adjusted, the 20 said spring, which is fixed at 39 to the lower leg portion is continued in the form of a wire through a brass tube 40 imbedded in the heel, and is finally connected to the hook of an adjustable turnbuckle 36, the 25 other extremity of which is hooked to a rod 38 fixed at the extremity 3 of the foot.

The complete apparatus is supported by a suspension device of special form which is shown diagrammatically in Figure 7. 30 The actual suspension device is in two parts, the part 41 takes the form of a somewhat wide band and the part 42 on the other hand comprises an ordinary catgut cord.

On this cord a roller 45 can move, the 40 roller being connected to an intermediate flexible suspension 43, the length of which can be adjusted. At the other extremity of this part a second roller 45 is fixed, on which a second catgut cord 44 can move, 45 the ends of this cord being fixed at 17—17, Figures 1, 2 and 7. This suspension arrangement does not inconvenience the amputated subject in any way and adjusts itself automatically to the body, and owing 50 to its light weight does not cause the wearer to become unduly heated.

The lower leg portion is constructed in a special manner, the plastic material surrounding a frame of steel wire uprights tied together at suitable points. This detail is not shown in the figure. The vertical steel wires are placed at the front and rear of the prosthetic column in order to form a light armoured beam possessing considerable strength.

Figures 11, 12, 13 and 14 illustrate modifications of the parts described above. In Fig. 11 the part 46 which slides into part 47 carries at its lower end a rack 48 with 60 which a double-toothed pawl 49 engages, a

small spring 50 holding this pawl in position. In order to adjust the height it is only necessary to press the end of the pawl 49 in order to release the part 46 for the purpose of lowering or raising it, the teeth 70 of the pawl being allowed to engage with the rack. This operation can be carried out with the greatest facility when required by the amputated subject.

At the upper part of the thigh pieces the 75 flexibility of the support was obtained as described above by means of springs which were wound on the part in question and were not protected. This arrangement, which possesses certain disadvantages, is 80 here replaced by a part 51, Figures 11, 13, and 14 which permits the springs to operate in a more efficient manner and enables them to be protected from contact with the garments.

The part 51 is located between the upper 85 end of the thigh pieces and the actual thigh or hip support.

Part 51 is composed essentially of a metal covering forming a box in which two spiral 90 springs 52 are located, these springs working under compression. The box protects them and serves as a guide. The two springs are compressed by a small cross-piece 53 which forms a piston in the box 95 51, a belt holder 54 terminating in a threaded rod, and a screw 55 completing the arrangement. At the lower end of the part 51 a hole 56 is provided by means of which the part is fixed by a bolt and screw to the 100 upper end of the thigh piece 46, Figure 11, so that it can be adjusted to any desired position when oscillating around the bolt. The belt which takes the load transmitted by the hip is provided at its extremities with 105 two series of eyelet holes 58, Figure 11, by means of which it is fixed by passing a lace through the holes. The mounting and dismounting of the apparatus as well as the adjustment can thus be effected in a very 110 convenient manner.

The modification to the belt or garter 59 has been made with a view to obtaining an easier method of dismounting the apparatus. The two pieces 47—47 pass between the actual belt 59 and two additional pieces 60 are tightly secured to the belt 59 on each side of the latter. The belt is fixed to the part 47—47 by means of two small bolts fixed to supports 47—47, which are passed through 115 corresponding holes in the parts 60—60, the whole apparatus being secured by nuts 61—61. In order to dismount it, it is only necessary to release the nuts 61—61 and cleaning can thus be very conveniently carried out.

What I claim is:

1. An artificial leg, embodying a thigh portion, a lower leg portion and a foot portion, said thigh portion comprising a pair of complementary uprights hinged to the 120

130

- lower leg portion and provided with a flexible and adjustable seat for supporting the hip bone of the wearer, said seat consisting of an oscillating band having its ends pivoted to the upper ends of said uprights and means for adjusting the height of said band. 5
2. An artificial leg, embodying a thigh portion, a lower leg portion and a foot portion, said thigh portion comprising a pair 10 of complementary uprights hinged to the lower leg portion and provided with a flexible seat for supporting the hip bone of the wearer, said seat consisting of an oscillating band having its ends pivoted to 15 the upper ends of said uprights, adjustable springs for suspending each end of the oscillating band and means for adjusting the height and length of said band. 20
3. An artificial leg, comprising a thigh portion, a lower leg portion, and a foot portion, and a universal joint connection between the lower leg portion and said foot portion, said universal joint connection consisting of transversely arranged compression 25 springs providing for the lateral play of said foot portion, an inclosed spring-controlled piston device connected to the rear of said foot portion, and a flexible and extensible stay secured to the front thereof, 30 all of said flexible and extensible connections having their upper ends secured to the lower leg portion. 35
4. An artificial leg, comprising a thigh portion, a lower leg portion, and a foot portion, said thigh portion being eccentrically connected to the lower leg portion, and a universal joint connection between the lower leg portion and the foot portion, said universal joint connection consisting of trans- 40 versely arranged compression springs providing for the lateral play of said foot portion, an inclosed spring-controlled piston device connected to the rear of said foot por-

tion, and a flexible and extensible stay secured to the front thereof, all of said flexible and extensible connections having their upper ends secured to the lower leg portion. 45

5. An artificial leg, comprising a thigh portion, a lower leg portion, a foot portion, and a flexible and extensible suspension device, said device consisting of two members, one of said members being supported from the shoulder of the wearer and the other secured to the lower leg portion, an eccentric connection between the thigh portion 55 and the lower leg portion and a universal joint connection between the lower leg portion and said foot portion. 60

6. An artificial leg, comprising a thigh portion, a lower leg portion, a foot portion, and a flexible and extensible suspension device, said device consisting of two members, one member thereof being supported from the shoulder of the wearer and the other secured to the lower leg portion, an intermediate extensible device interposed between said suspension members, an eccentric connection between the thigh portion and the lower leg portion, and a universal joint connection between the lower leg portion and said foot portion, said universal joint connection consisting of transversely arranged compression springs providing for the lateral play of said foot portion, an inclosed spring-controlled piston device connected to the rear of said foot portion, and a flexible and extensible stay secured to the front thereof, all of said flexible and extensible connections having their upper ends secured to the lower leg portion. 75

In testimony whereof I affix my signature, in presence of a witness.

ANDRÉ BEURDELEY.

Witness:
